UNITED STATES PATENT OFFICE.

JOHN W. MEAKER, OF DETROIT, MICHIGAN,

SPARK-PLUG.

1,073,270.

Specification of Letters Patent. Patented Sept. 16, 1913.

Application filed March 25, 1912. Serial No. 685,934.

To all whom it may concern:

Be it known that I, JOHN W. MEAKER, a citizen of the United States of America, residing at Detroit, in the county of Wayne 5 and State of Michigan, have invented certain new and useful Improvements in Spark-Plugs, of which the following is a specification, reference being had therein to the accompanying drawings.

- 10 This invention relates to improvements in spark plugs and its object is to provide a simple, cheap and efficient construction in which the insulating member is quickly insertible in the bushing and may be adjusted therethrough to any desired position, and also embodying a construction of transparent head with a spark gap therein, having certain new and useful features all as hereinafter more fully set forth.
- 15 The invention consists in the matters hereinafter set forth and more particularly pointed out in the claims reference being had to the accompanying drawings in which—

- 20 Figure 1 is a vertical section through a spark plug embodying the invention; Fig. 2 is a section of the same on the line 11—11 of Fig. 1; Fig. 3 is a detail showing an inverted plan view of the transparent head; Fig. 4 is an elevation of the lower end of the spark plug; Fig. 5 is a longitudinal vertical section through a spark plug embodying a modified construction; and Fig. 6 is a similar view showing a further modified 25 construction.

As shown in Fig. 1, a bushing 1 is formed in the usual manner with an externally screwthreaded portion to engage a screwthreaded opening in the cylinder of an engine and also formed with a hexagonal head portion for the engagement of a wrench by means of which the bushing is screwed into place. The hexagonal head is preferably provided with a number of grooves 2 to give a greater radiating surface to the head so that it will cool rapidly. The bushing is formed with an axial bore extending therethrough and it is preferably internally screwthreaded throughout its length to receive an externally screwthreaded tubular member or binding sleeve 3 which is formed with flattened sides at its inner end forming a wrench hold 4 by means of which the sleeve may be screwed into the bore of the bushing. The inner or upper end of the sleeve 3 forms a shoulder to support the in-

sulating plug 5 which is preferably formed of porcelain in the usual manner with an annular rib 6 intermediate its ends which fits within the bore of the bushing and forms shoulders adapted to be engaged by suitable packing rings 7, one of said rings being interposed between the shoulder and the inner end of the sleeve 3. Externally screwthreaded locking rings 8 and 9 are screwed into the upper end of the bore of the bushing with one of the packing rings interposed between the locking ring 8 and the upper shoulder on the insulating plug. The ring 9 forms a locking ring for the ring 8 and both rings are provided with notches in their upper edges for the engagement of a tool by means of which the rings are screwed into the bore to firmly lock and hold the insulating plug in place. Obviously the insulating plug may be adjusted within the bore by adjusting the sleeve and locking rings which form movable shoulders within the bushing to clamp the rib on the plug between them.

80 A rod secured in the usual manner in an axial bore in the insulating plug forms an electrode 10. The lower projecting end of the rod is reduced in diameter and the lower end of the sleeve 3 is preferably partially closed by a plate 11 having an axial opening through which the end of the electrode projects. The plate is also provided with a plurality of openings 12 surrounding the center opening and cutting into said 85 opening so that a plurality of sparking points is formed on the plate around the electrode of the plug. An inwardly projecting flange 13 at the extreme lower end of the sleeve 3 forms a seat for the plate 11 and 90 this plate is preferably made of a nickel alloy or other suitable metal not readily destroyed by heat.

95 The head of the bushing 1 is formed with an upwardly extending tubular portion 14 which is enlarged at its upper end and internally screwthreaded to form a socket to receive a head 15 which is preferably formed of glass or other transparent material. This transparent head is externally screwthreaded at its lower end to engage the socket 14 and is seated within the socket upon a shoulder 16 formed by the enlarged upper end of the tubular extension of the bushing, which tubular portion is formed with a series of 100 air holes 17 below the socket 14 to admit air to the interior of the head and cool the 105

same so that the glass will not become overheated and crack.

The upper projecting end of the electrode 10 within the insulating plug, is also reduced in diameter and is spaced from a second electrode 18 which is carried by a cap 19 fitting upon the upper end of the head 15. A series of grooves 20 in the upper end of the head permit a circulation of air through the head beneath the cap. A suitable plate or spider 21 is secured to the rod forming the electrode 18 near the inner end thereof to engage suitable seats or notches formed in the inner side of the head 15 and the outer end of the rod projects through an opening in the cap 19 and is screwthreaded to receive a binding nut 22 by means of which the cap is secured in place and the electrode adjustably held. The rod forming the electrode preferably engages a screw-threaded opening in the spider 21 so that said rod may be adjusted through the spider to move its sparking point toward or from the sparking point of the electrode 10.

In this construction the spark gap is located within a head formed entirely of glass or other transparent material so that the spark may be readily observed and the construction is such that the head is ventilated and thoroughly cooled to prevent the cracking of the glass.

In Fig. 5, a construction is shown in which the socket for receiving the transparent head 30 is formed integral with the upper end of an externally screwthreaded sleeve 23 adapted to be screwed into the upper end of the bore of the bushing. As in the construction shown in Fig. 1, this socket 24 is internally screwthreaded to receive the screwthreaded lower end of the transparent head 25 which seats within the socket and a series of holes 26 for ventilating the head are formed in the tubular extension of the sleeve. The lower end of this sleeve 23 forms a shoulder to engage the upper washer 7 which is imposed between the end of the sleeve and the annular rib 6 on the insulating plug.

In the construction shown in Fig. 6, the spark gap and transparent head are dispensed with and the bushing 27 is formed as in the other constructions with an axially screwthreaded bore, but the screw thread is stopped at a short distance from the lower end of the bore to form a stop 32 for the lower sleeve 33 which is formed through screw threads at its upper end only, the remainder of the sleeve being formed plain so that it will pass through the plain lower end 60 of the bore. Said sleeve 33 is thus held by its screw threads against any possibility of working loose and dropping out, and it may be readily screwed into the bore from the upper end thereof. The upper or inner end 65 of the sleeve 33 forms a shoulder to oppose

the lower shoulder on the insulating plug 29 formed by the annular rib thereon, and the inner end of the screwthreaded sleeve 28 which is screwed into the upper end of the bore, forms a shoulder to oppose the upper shoulder on the plug. The said insulating plug is thus held by clamping its rib between said sleeves with the packing rings 7 interposed between their inner ends and the said shoulders formed by the rib. When so held, the upper end of the plug extends outwardly through the outer open end of the ring 28 and the electrode 30 extends outward through the outer end of said plug where it is provided with a binding nut 31 for attaching an electrical conductor thereto.

This construction of spark plug is very cheap to manufacture owing to the construction of the bushing with its axial screwthreaded bore and the sleeves therein which form adjustable seats for the insulating plug.

Obviously, changes in the construction and arrangement of parts may be made without departing from the spirit of my invention and I do not wish to limit myself to the particular form and arrangement shown.

Having thus fully described my invention what I claim is:—

1. In a spark plug, the combination of a bushing having an axial screwthreaded bore of uniform diameter extending through the bushing, an insulating plug in the bushing formed with an annular rib, externally screwthreaded tubular members within the bushing surrounding the upper and lower ends of the insulating plug and forming shoulders at their inner ends to oppose the shoulders formed by the rib on the plug, an electrode carried by the insulating plug and extending longitudinally therethrough, a tubular extension on the bushing provided with air openings and formed with a seat, a transparent head having open ends and seated within said seat, an electrode extending through the upper open end of the head, and means for adjustably securing the electrode in place upon the head with its inner end spaced from the electrode carried by the insulating plug to form a spark gap within the head, the sleeves and plugs being together longitudinally adjustable in the bushing, and an electrode on the lower sleeve in operative relation to the plug electrode.

2. In a spark plug, the combination of a bushing formed with an axial screwthreaded bore of uniform diameter extending therethrough and provided with a hexagonal head having peripheral slots cut therein to increase the radiating surface of said head, an insulating plug having an enlargement intermediate its ends forming an upper and a lower shoulder thereon, an electrode in the longitudinal axis of said plug with its ends projecting beyond the ends of the plug, a sleeve having screw threads at its upper

end to engage the screwthreaded bore and formed with a plain lower end, the screw thread of the bore being stopped at a distance from the lower end of the bore to form a stop for the sleeve, and an externally screwthreaded member screwed into the bore above the enlargement on the insulating plug, the sleeves and plugs being together longitudinally adjustable in the bushing, and

an electrode on the lower sleeve in operative relation to the plug electrode.

In testimony whereof I affix my signature in presence of two witnesses.

JOHN W. MEAKER.
